UNITED STATES PATENT OFFICE

161,305

INFLATABLE TOY FIGURE

Morton M. Bernstein, Manhasset, N. Y., assignor
to Plastikaire Products Inc., Queens Village,
N. Y., a corporation of New York

Application August 14, 1950, Serial No. 11,758

Term of patent 7 years

(Cl. D34—15)

To all whom it may concern:

Be it known that I, Morton M. Bernstein, a citizen of the United States and a resident of Manhasset, in the county of Nassau, State of New York, have invented a new, original, and ornamental Design for an Inflatable Toy Figure, of which the following is a specification, reference being had to the accompanying drawing forming part hereof, in which:

Fig. 1 is a side view of an inflatable toy figure, showing my new design;

Fig. 2 is a plan view thereof;

Fig. 3 is a front view thereof; and

Fig. 4 is a rear view thereof.

I claim:

The ornamental design for an inflatable toy figure, as shown.

MORTON M. BERNSTEIN.
